(57) **CLAIM**

The ornamental design for a golf ball, as shown.

DESCRIPTION

FIG. 1 is a perspective view of a golf ball of the present invention;

FIG. 2 is a front view thereof;

FIG. 3 is a left side view thereof;

FIG. 4 is a right top view thereof;

FIG. 5 is a side view thereof; and,

FIG. 6 is a bottom view thereof.

A rear view of a golf ball is omitted since no claimed
ornamentation is found thereon.

The portions shown in broken lines are for illustrative
purposes only and form no part of the claimed design.
